CARPENTER'S READILY CLEANABLE
HAND PLANE

Lawrence E. Pratt, Bedford, Ohio; Amber C. Pratt,
executrix of Lawrence E. Pratt, deceased, as
signor to Amber C. Pratt, Bedford, Ohio

Application June 2, 1947, Serial No. 751,668

14 Claims. (Cl. 145—5)

1

This invention relates to carpenters' readily cleanable hand planes for planing wood.

Ordinary hand planes while in use tend to plug or load up with shavings and do not do the work for which they are designed. This plugging or loading up occurs in the space between the blade and the adjacent forward edge of the opening, slit or throat in the base for the blade. In many instances the cutting-blade assembly must be removed in order to clean out the plugged shavings. The plane must then be reassembled and generally the blade readjusted so as to make the proper cut. This may occur time and time again throughout the day's work, thus taking up and wasting considerable of the carpenter's or operator's time.

It is an object of this invention to produce a hand plane having provision for readily cleaning the same of the shavings caught therein and any dust or particles remaining in a moment's time and without disturbance of the blade's adjustment or possibility of damage thereto.

A further object is the provision of a plane of conventional form and appearance, which has been so satisfactory to the artisans for so many years, and of substantially the same tried and proven construction for the planing operations, but having means for readily cleaning the same of the caught shavings without annoyance to the user and practically without interruption of the work and without detracting from the form, appearance, strength or structural qualities of the conventional plane.

A further object is the provision of a plane in which the portion of the base in front of the blade may be substantially instantly removed and reinserted for cleaning out the shavings without disturbance of the blade assembly or possibility of damage thereto.

A still further object is the provision of such a plane in which the front operating knob of the two-hand plane is carried by the removable plate and serves as a handle therefor in such removal and insertion, whereby the cleaning out of plugged shavings may be accomplished with ease, celerity and safety, and without the necessity of removal of the hands from the operating knobs or substantial interference with the planing operation.

Still further objects and advantages will appear from the description and claims to follow, in connection with the accompanying drawing which illustrates, by way of example and not of limitation, embodiments of the invention, and in which —

2

Fig. 1 is a slide elevation of a conventional two-hand plane with the fore part broken away to show this invention in longitudinal central section;

Fig. 2 is a bottom plane view of the same and showing the opening in the base in advance of the blade and the removable section or plate thereof;

Fig. 3 is a side view of the front end of the plane with the near side member broken away and showing the cross brace and base or bottom of the plane in section and the removable base section or plate tipped up substantially as it would be in inserting it into the plane body or in removing it therefrom;

Fig. 4 is a cross section of the plane on the line 4—4 of Fig. 1 through the throat of the plane, showing the cross brace, the side members of the plane and the removable plate in relation thereto when the plate is in the plane ready for use;

Figs. 5 and 6 are bottom views of the removable plate showing the unlocked and locked positions of the partially rotatable clamping cam disc in the lower face of the overlapping end of said plate and its relation to the locking and clamping lug on the base of the plane, the said lug being sectioned in the plane of the lower face of the rotating cam, said cam disc being secured to and so rotatable by the knob or handle of the plane on the upper side of said removable plate;

Fig. 7 is a top plan view of said removable plate or member;

Fig. 8 is a detailed perspective view of the locking cam and its upper side construction by which it is secured in the removable plate and to the knob or handle thereof;

Fig. 9 is a side view of the same;

Figs. 10 and 11 are respectively perspective views of the plane body and the removable plate, the two being separated as they would be for cleaning out the clogging shavings, the plane body being held in one hand by its handle and the removable plate in the other hand by its knob or handle which is the other handle of the plane, whereby the obstructions may be removed and the cleaning accomplished almost instantaneously, with practically no interruption in the work of planing and with entire safety to the cutting edge of the blade and with no readjustment of the latter for cutting in the use of the plane; and

Fig. 12 is a view similar to Fig. 1 but showing the removable cleaning plate applied to a small one-hand plane, that is, one that does not have

a front knob or handle for the use of the plane in planing.

Referring to these drawings, the plane shown is preferably of conventional type having a metal elongated narrow body 20 which may be cast and comprises the flat bottom or bottom member 21 and sides or side members 22 extending along the long opposite edges of the bottom. A wooden or equivalent handle 23 is secured to the top of the base or bottom 21 at the rear end and midway of the sides 22, and is grasped by the hand to manipulate the plane. The usual blade assembly is provided between the sides, including the blade 24, the guard plate 25 and clamp 26, the sheet metal triangular form 27 secured to a slightly raised part of the upper side of the base, on the sloping front side of which the blade rests and is carried, and the nut and lever adjustment 28 of the blade as well as its lateral adjusting lever 29 carried by said form 27 and by which the position of the blade and its cutting edge in the mouth or throat of the plane may be accurately adjusted. All of this may be, and as shown is, of the usual construction in conventional planes. Such planes also have the cross brace 30 extending between the sides of the plane in advance of the blade, which strengthens the sides and body structure of the plane.

In all planes the adjustment of the blade to produce the desired cut is important and so far as possible, once set, should not be tampered with. The protection of the cutting edge of the blade is most essential, since any injury thereto spoils the work and makes it necessary to remove and resharpen or replace the blade and adjust it all over again.

But such planes while in use will plug or load up with shavings and prevent them from doing the work for which they were designed. This plugging or loading up occurs in the space between the blade and the edge of the base in front of the same in the opening through which the blade projects. This opening in the base is variously called the mouth or throat and the front edge thereof is usually slightly slanted upwardly and forwardly to provide room for the movement of the shavings as formed in the use of the plane.

In many instances the cutting blade assembly must be removed in order to clean out these plugged-in shavings. The plane then must be reassembled and generally the blade must be readjusted so that it will again cut properly; and this may occur time and time again throughout the day's work, thus taking up and wasting considerable of the carpenter's time, aside from the annoyance to him or the operator.

In order simply and instantly to clean out or remove these plugged shavings from the plane without disturbing the cutter blade assembly in this invention, a section of the working base of the plane in advance of the blade is made readily removable and replaceable, whereby the shavings may be freed and shaken or blown out and most of the operator's valuable time formerly wasted is saved. Thus, as indicated in the drawings, a rectangular opening in the normal base 21 of the plane is formed extending between the sides 22 of the plane and forwardly from the blade underneath the cross brace 30 to a point in advance of said brace and forming the edge 31 across the original or normal base of the plane which extends to the front end of the plane. The front end of the plane body is thus left substantially

intact and not appreciably weakened by the base opening.

The removable section 32 of the base, which is relatively thick and heavy, accurately fits the said opening from said edge 31 rearwardly and substantially to the blade, the rearward edge of which section forms the front edge of the throat opening for the blade and is bevelled upward accordingly, as at 33. This section thus forms a rigid part of the working flat base or bottom of the plane when it is in position therein, and its lower surface is ground in assembly with the entire base of the plane body, so that it may be used with the greatest efficiency therein.

This removable section 32 of the base, as shown, forms an offset end of a plate, the other end 35 of which is adapted to overlap or overlie the forward end of the base plate of the plane when the base section is in place therein, the shoulder connecting the two lower surfaces forming edge 36 which abuts base edge 31, as in Figs. 1 and 2, at such time. The forward edge of the plate 35 may extend to the forward edge of the base plate of the plane and be curved to conform thereto and bevelled or curved rearwardly at the edge to produce a rounded edge on the front of the plane when the plate is in place therein.

This offset plate is provided with a knob or handle 37 on its forward part and is adapted to be inserted in and withdrawn from the plane through the space between said base edge 31 and the cross brace 30 when tipped up transversely to the plane, as indicated in Fig. 3. The two may be entirely separated and are intended so to be in normal cleaning, as shown in Figs. 10 and 11 combined. The handle 37 serves as a means not only to manipulate this removable plate but as a front handle for the plane itself. It is preferably of similar size, shape and appearance as the conventional front handle of such planes and is used naturally in the same way by the carpenter in planing.

When the removable plate is in final position in the plane, the upper side of the rear end engages the lower edge of the cross brace 30 and is pressed up against the same as a stop, as later explained, and such engagement preferably includes the slightly raised lug 38 on the upper side of the plate end 32. This is a manufacturing convenience, since it renders unnecessary the accurate fitting across the full width of the top of the end 32 with the bottom of the cross bar.

This removable plate also fulcrums over the base edge 31 or the upper corner thereof in inserting and removing the same from the plane body and bears along the same when in final position in the plane. This is insured by providing a slight space between the lower side of the end 35 of the plate and the upper face of the base plate 21 forward of said edge 31. This may be conveniently done by inclining the plane of said lower face of the end 35 slightly upward so as to provide a slight clearance, as at 40, Fig. 1, from the top of the base. The lower faces of the ends 32 and 35 are therefore not in exact parallelism. Accordingly, when the plate is in final position and the end 35 is pressed toward the base or clamped in that position, it acts like a lever fulcrummed at the edge 31 and stopped by the cross brace on the top of end 32, and the end 32—the base section—is exactly and firmly held in place. The plate is thus subjected to a bending moment or stress, and thus the base section is at all times firmly and exactly placed and held in position, acting practically as an integral

5

portion of the base so far as concerns the use and working of the plane in planing.

Besides, such a clearance and poised method of holding the plate between bearings renders unnecessary the machining of the upper face of the base (which may be of cast metal) at the front end of the plane to provide a suitable seat for the end 35 of the plate, or to make it at the exact angle to be in parallelism with the bottom plane of the base in order to make the removable section fit flush therewith.

With such a poised plate, suitable tension means is provided constantly to exert pressure or pull upon the end 35 to force it toward the base 21 beneath it. This may take the form of spring-pressed balls 41 seated in the opposite side edges of the end 35 of said plate. These balls are seated in holes in said edges on relatively strong coil springs therein, the metal of the edges being upset toward the balls outside the medial planes thereof so as to prevent the balls from being sprung out the holes when the plate or its end 35 is outside the side members 22 of the plane body. At the same time the balls project appreciably beyond the said edges when not compressed.

Co-operating with said balls are suitable depressions or recesses 42 in the inside faces of the sides 22 of the body, which are so located with reference to the balls when the end plate 35 is in final position that the balls constantly tend to force or pull the end 35 of the plate toward the base plate 21, whereby the said removable plate is placed under a bending stress and is exactly held in position over the edge 31 as a fulcrum and under the cross brace as a stop.

This method of holding the removable section of the base in working position suffices for small block or one-hand planes such as that of Fig. 12, where there is no front knob to be grasped by the hand of the operator during planing or in which the front knob may be supported otherwise than on the front end of the removable plate; but where, as here, the front knob is located on the front end of the said plate, it is preferred that a special or positive lock or retaining means be provided for said plate when in its home position. Thus, in its present preferred form, a rotary cam in disc-like form is located in a shallow recess in the under side of said end 35 of the plate and is secured to the handle 31 or the handle is secured to it, as will be explained, so that the cam may be rotated through its clamping and locking arc by the handle. This cam is arranged to engage or disengage, in such rotation, a clamping and locking lug or boss on the base, whereby the handle not only serves for the manipulation of the removable plate and the operation of the plane but also as a lock operating means for the plate.

The device itself is comparatively simple. The cam member and its handle-engaging means is shown in perspective in Fig. 8, in side view in Fig. 9, in a cross section of the assembly in Fig. 1, and in the relation of the locking cam to the locking lug in Figs. 5 and 6.

As seen in Figs. 8 and 9, the locking member has an enlarged disc-like lower end 43 with a sloping cam edge 44 extending substantially half way around the same and a bearing portion 45 and sleeve or shaft portion 46, an internally threaded hole extending axially through the member and the stem or shaft portion, as indicated, being externally fluted or straight knurled. The end 35 of the plate has a counterbored

6

aperture therethrough to receive in its lower face the disc-like end 43 and cam 44 of the locking member, as shown in Fig. 1, and the bearing portion 45 of said member. These are rotatable in the said end 35 throughout the locking arc. A pin 47 is driven through the end 35 and projects into a cut-away portion of edge cam 44 of the locking member to limit the rotation of the cam to the locking arc.

A metal disc or washer 48 at the lower end of the wooden handle or knob 37 rests on the shoulder 49 of the locking member (Figs. 8 and 9) and the handle is pressed tightly down over the stem 46 and against said washer. A long screw 50 extends through the handle and threads into the stem or sleeve 46 and tightly binds the locking member washer and handle together, the fluting or knurling on sleeve 46 assisting in preventing the handle rotating independently even under the clamping torque of the lock. The shoulder 49 and washer prevent the clamping of the parts to the end 35 in a way to prevent rotation of the handle and locking cam, yet they are firmly attached thereto for all other purposes.

A locking screw 51 inserted below the screw 50 engages its end and prevents it from becoming loose.

A circular boss 52 with an undercut head, as at 53 (Figs. 5 and 6), on the base 21 is adapted to enter a recess 54 in the lower face of end 35 of the removable plate adjoining the recess for the cam disc 43 when the plate is down upon the base. The cam 44 on the disc 43 is wide enough to reach into the undercut 53 of the boss 52 and under the overhanging head of the boss.

The result is that when the lock is turned by the handle, say to the left, until it strikes the pin 47 (Fig. 5), the end 35 of the removable plate may be raised or lowered free of the boss 52, and when the said end of the plate is down on the base, by the turning of the handle to the right the thin edge of the sloping cam 44 is caused to enter beneath the overhanging head of boss 52 and as the turning continues the head rides up on the cam, the extreme position being indicated in Fig. 6, and the said end of the removable plate is firmly clamped and locked to the plane, the base section of the plate being firmly held in position by the bending moment or stress thereon of the clamping action. This locking and unlocking of the plate is by a simple fractional turn of the handle or knob 37 and may be readily accomplished by a slight twist of the wrist while holding the knob in the hand for the purpose of removing or inserting the plate in the plane. It is thus practically automatic and very effective.

As heretofore stated, the cutting edge of the blade is protected against contact with the removable plate in the manipulation of the latter in being taken out of and inserted in the plane body in order to clean out the plugged shavings and debris. This is preferably provided for by the curved cam surface 60 on the upper side of the plate back of the handle or knob 37 and in front of the cross brace 30 when the plate is in position. This curved surface is adapted to strike against the cross brace and pushes the said plate forwardly against the edge 31 as the plate is rotated forwardly after being inserted in the plane. This keeps the plate out of contact with or striking against the blade edge. Similarly when rotating the plate toward the open position to take it out, the same cam surface

keeps it back and away from the cutting edge of the blade.

The spring balls, though not necessary in this two-handed plane for holding the removable plate under stress in its final position during planing, do have a beneficial effect in tending to urge the plate to its final position in which the lock can be operated by the handle, in centralizing the plate between the side rails 22 of the plane when the plate after being dropped into the plane is rotated about the edge 31 by pressing forwardly on the handle 37, and also in riding forwardly for a short distance along the top edges of the side rails in the first part of the rotative movement of the plate resulting from the forward pressure on the handle to seat the plate, this riding along insuring the lifting and pulling of the shouldered edge 36 of the plate up and forwardly against the fulcrum edge 31 of the base and keeping it there in the initial forward rotative movement of the plate and handle toward seating position. Fig. 3 illustrates what is meant, the balls 41 resting on the tops of side rails 22 when the plate is first inserted in the plane. They may act as stops to prevent the plate from passing too far through the opening when inserted therein transversely of the plane, and then, if it hangs loosely therein, ride along the tops of the rails at the first forward pressure on the handle and thus keep the shoulder 36 up against the edge 31. This makes for ease and certainty of operation without care or attention on the part of the operator.

The lower corner edges along the raised end 35 of the plate are preferably slightly curved, as at 61 (Figs. 5, 6 and 11), for ease of entrance of said end between the sides 22 of the body when being turned down to final position and to avoid obstruction by the corner fillets in the casting, as at 62 (Fig. 10). The corners at the juncture of the cross brace 30 with the side rails 22 of the plane are usually rounded or have fillets, and the corners of the cam 60 on the upper side of the removable plate are likewise rounded, as indicated in dotted lines at 63 in Fig. 2.

The operation of the invention will be apparent from the foregoing. With the removable section in place, the plane is used in the usual manner of the conventional two-hand plane, the main handle 23 being grasped in one hand, usually the right hand, and the other handle or knob 37 being held in the other hand. Although this knob 37 is located on the removable section or plate, it serves in the normal way as the front handle of the plane in working. So far as this is concerned, the knob or handle 37 is substantially the same and located in substantially the same place at the front end of the plane as in the conventional plane with which the carpenter is familiar.

When the plane plugs up with shavings, all the carpenter has to do is to give the front handle a little twist and lift the removable plate free from the plane. This he may do without letting go of the handles of the plane; the partial twist of the handle 37 unlocking the cam 44 in the removable plate from the lug 52 on the base, and the plate, tipping up and withdrawing freely from the plane body which is held by the other hand. During this operation, the cam surface 60 on the removable plate and the cross brace 30 prevent any possibility of contact with the cutting edge of the blade and injuring the same. The blade assembly is not touched or removed or its adjust-

ment interferred with and does not have to be replaced, reassembled or readjusted.

The removal of the plate from the plane, as stated, permits the shavings to fall free and any dust or particles may be easily removed from the plane or plate by a quick shake of either or both while still holding them in the hands, or by blowing upon them.

The plate is then inserted in the space in advance of the cross brace by tipping it up relatively to the plane and inserting it transversely therethrough, which may readily be done without releasing either part of the plane from the hands, and then pushing forwardly on the handle 37 and giving it a slight twist when the end 35 is seated. The operator need exercise no especial care in doing this. The spring balls 41, the cam 60 and the cross brace 30 all prevent things going wrong, and the removable base section 32 is snugly landed in its proper position as a part of the working base of the plane and is firmly held therein in a state of stress between the cross brace and the fulcrum edge 31 of the base.

This is all done in a few seconds of time and the work of planing is scarcely interrupted, and is all accomplished without any interference with or readjustment of the plane blade assembly or injury to the cutting edge of the blade. Moreover, the plane body is not weakened practically by the short removable section of the base, since the fore part of the base, the sides and cross brace remain intact, the same as in the usual plane. The front handle is sturdily applied, the removable plate as a whole is of relatively heavy construction, and is firmly held in place so that the removable section of the base forms a part of the plane base for all normal working and purposes.

For small one-hand planes such as that indicated in Fig. 12, where there is no front working handle of the plane, the same construction of removable plate may be employed as in the two-hand plane described, with the exception that the spring balls alone may be relied on to hold the plate in position under tension over the edge of the base plate as a fulcrum and under the cross brace as a stop, and a small knob or finger piece is attached to the plate to assist in its removal and replacement. No other lock need be provided.

Thus, as indicated in said Fig. 12, the spring balls 70, corresponding to and the same as balls 41 in the first form, are provided and they operate in the same way as described for balls 41. The cam disc lock and handle on the plate are omitted and a small knob, as finger piece 71, may be attached to the upper side of the forward end of said removable plate. The cross brace 72 is indicated in dotted lines and corresponds to the cross brace 30 of the first form. The construction, arrangement and operation are the same as in the first form except for absence of lock and handle. In use, when the plane becomes clogged with shavings, it may be readily cleaned by pulling the plate by the knob or finger piece 71 into its tipped-up position, the offset shoulder and base plate edge acting as a fulcrum for such rocking of the plate. The plate is then withdrawn from the plane by the fingers grasping the knob, the shavings shaken or blown out, and the plate returned to the plane by first inserting it transversely in advance of the cross brace and then pressing its upper end forwardly to rock it over the fulcrum edge and shoulder into position. The spring balls and their recesses in the side mem-

bers of the plane, as explained in connection with the first form, hold the plate in final position under stress over the fulcrum and under the cross brace as a stop. Since there is no pull back on the knob or finger piece 71 during the use of the plane, a positive lock like or corresponding to that of the first form is not needed, although one could be supplied, if desired, and suitably operated by the finger piece 71.

Further description of this type of plane of Fig. 12 is deemed unnecessary, since, as stated, the difference from that described in detail above, save for size, is in the omission of the positive cam lock and the handle which forms the front operating handle of the plane.

Having thus described the invention, what is claimed and desired to be secured by Letters Patent is:

1. A hand plane comprising an elongated trough-like metal body having a planing base with an opening therein and side members along the base, a cutting blade assembly and operating handle mounted on the body with the blade projecting through the said opening, a relatively heavy removable plate having transversely offset end portions lying in different planes, one end portion of which plate is adapted to fit and fill in said opening in the base forward of the blade to form a portion of the said planing base, a back stop abutted by the upper side of said one end portion of said plate when the latter is in planing position in said opening in the base, the other end portion of which plate is adapted to overlie the base in advance of said opening and rockably to bear upon the edge of the base at said opening, and clamping means to press the said overlying end portion of said plate toward the base and thereby the other end portion of said plate up against said back stop in planing position in said opening, the widths of said opening in the base and of said plate enabling the said plate when unclamped to be inserted into the plane or withdrawn therefrom from the top side of the plane and to rock about said forward edge of said opening as a fulcrum in being inserted and positioned in or withdrawn from the plane.

2. The device of claim 1 in which the forward overlying end portion of said removable plate when in planing position is slightly spaced from the base in advance of the said fulcrum edge, and the clamping means places said plate in a state of stress over the said fulcrum and under the said back stop accurately and firmly to hold the said one end portion of said plate in planing position in the said opening in the base.

3. A hand plane comprising an elongated trough-like metal body having a planing base with an opening therein and side members along the base, a cutting blade assembly and operating handle mounted on the body with the blade projecting through the said opening, a cross brace between the side members spaced in front of the cutting blade, said opening extending forwardly of said brace, a relatively heavy removable plate having transversely offset end portions lying in different planes, one end portion of which plate is adapted to fit and fill in said opening in the base forwardly of the blade to form a portion of the said planing base, the other end portion of which plate is adapted to overlie the base in advance of said opening and rockably to bear upon the edge of the base at said opening, and clamping means to press the said overlying end portion of said plate toward the base and the said

one end portion up against said brace in planing position, the widths of said opening in the base and of said plate enabling the said plate to be inserted into the plane or withdrawn therefrom through the top side of the plane and to rock about said forward edge of said opening as a fulcrum in being inserted and positioned in or withdrawn from the plane.

4. The device of claim 3 in which the forward overlying end portion of said removable plate when in planing position is slightly tilted up from the base in advance of said fulcrum edge, whereby the clamping means when tightened stresses the said plate over said fulcrum edge and under said brace to hold the said one end portion of said plate firmly and accurately in said opening in the base.

5. A hand plane comprising an elongated trough-like metal body with a planing base and opening therein and side members along the base, a cutting blade assembly and operating handle mounted on the body with the blade projecting through the said opening and a cross brace between the side members suitably spaced in front of the blade, said opening extending from the blade to a point forwardly of said cross brace, a relatively heavy removable plate having laterally offset end portions lying in different planes, one end portion of which plate is adapted to fit and fill in said opening in the base forwardly of the blade to form a portion of the planing base and the front edge of a blade throat, the other and forward end portion of which plate is adapted to overlie the base in advance of said opening and to bear upon the front edge of said opening, said forward portion of said plate being slightly spaced from the base forward of said edge of the opening when the plate is in planing position in said opening, said plate being adapted to be inserted transversely in the plane from the top through the space between the cross brace and the front edge of said opening and then to be rockable about said edge into planing position and to be withdrawn from the plane in the same way for cleaning purposes but in the reverse order, said plate having a cam portion on its upper side engaging the said brace during such rocking movement to guide the plate into and out of its planing position and prevent contact of the plate with the said blade, said plate when in planing position bearing against said brace as a back stop and upon said edge of the opening in the base as a fulcrum, and clamping means to urge the overlying end of said plate toward the base to place said plate under bending stress over said fulcrum edge and under said brace tightly to hold said one end portion of the plate in planing position in the said opening in the base.

6. The device of claim 5 having a knob carried by said overlying end portion of said removable plate, said knob serving as a handle for the manipulation of the plate in its removal from the plane for cleaning purposes and its reinsertion in the plane for planing, said knob also serving as an operating front knob of the plane in planing.

7. The device of claim 6 in which the said clamping means is controlled by said knob for clamping said removable plate in planing position in the plane.

8. The device of claim 7 in which the clamping means comprises a rotary cam carried by said overlying end portion and controlled by said knob, and a cam lug mounted on said base and adapted

to be engaged by said cam to press and clamp the said overlying end portion toward the base.

9. A hand plane comprising an elongated trough-like metal body with a planing base having an opening and side members along the base, a cutting blade assembly and operating handle mounted in the plane with the blade projecting through the said opening and a cross brace between the said sides suitably spaced in front of the blade, said opening extending between the sides and from the blade to a point forwardly of said cross brace, a relatively heavy removable plate having laterally offset end portions lying in different planes, one end portion of which plate is adapted to fit and fill in said opening in the base in front of the blade to form a portion of the plane base and the other end portion of which plate is adapted to overlie the base in advance of said opening and rockably bearing upon the edge of the base at said opening, said plate being adapted to be inserted transversely into the plane from the top through the space between the cross brace and the front edge of said opening in the base and to be withdrawn therefrom, said plate being rockable over said edge as a fulcrum to position the said one end portion in said opening for planing, said plate when in planing position bearing against said brace as a stop on the one side and upon said edge of the base as a fulcrum on the other side, and spring-pressed balls in the edges of said overlying end portion of the said plate engaging sockets therefor in the adjacent sides of the plane to hold the plate tightly in its planing position.

10. A plane having the features of construction set forth in claim 9 in which said balls are adapted to engage the top edges of the side members of the plane when the said plate is inserted transversely into the plane, thereby tending to limit the extent of such insertion and then to ride along said top edges when the plate is initially rocked toward planing position whereby to tend to hold the said plate in rocking position over said fulcrum edge, said balls being depressed by said side members in the further rocking of said plate to planing position, the said sockets and the bores containing the spring-pressed balls being out of axial alignment to produce a camming action of the balls in the sockets to hold the said plate under tension in planing position.

11. A hand plane having a planing base, a blade assembly in the plane, the base having an opening forming a throat for the blade, a removable section of the base filling in a portion of said opening in advance of the blade, a rigid holding member rigidly attached to said section and extending forwardly over the base in advance of said section, a hand knob carried by and secured to said member, said holding member and base section being rockable as a unit over the edge portion of the base at the forward end of said opening to swing the section down out of the base to free impacted shavings or the like in the plane and to swing the said section back into place in the base for planing after such cleaning,

and guiding means for preventing contact of the section with the blade in such movements.

12. A hand plane having a planing base, a blade assembly in the plane, the base having an opening forming a throat for the blade, a removable section of the base filling in a portion of said opening, a holding member rigidly attached to said section and extending forwardly over the base in advance of said section, said holding member and base section being rockable as a unit over an edge of the base at the said opening to swing the section down out of the base to free impacted shavings or the like in the plane and to swing the said section back into place in the base for planing after such cleaning, a stop member in the plane over said section against which the section abuts when in planing position in the base, and means to clampingly press the said holding member toward the base to hold the said base section tightly in planing position against said stop.

13. A hand plane having a planing base, a blade assembly in the plane, the base having an opening forming a throat for the blade, a removable section of the base filling in a portion of said opening, a holding member rigidly attached to said section and extending forwardly over the base in advance of said section, said holding member and base section being rockable as a unit over an edge of the base at the said opening to swing the section down out of the base to free impacted shavings or the like in the plane and to swing the said section back into place in the base for planing after such cleaning, a stop member over said section, and a cam portion on the top of said section and holding member adapted to engage said stop member to prevent contact of said section with the blade in the manipulation of the section and holding member with respect to the plane and longitudinally to position the said section in the base for planing.

14. A hand plane having a planing base, a blade assembly in the plane, the said base having an opening forming a throat for the blade, a removable section of the base filling in a portion of said opening, a forwardly extending holding member rigidly secured to said section by a jogged connection, said member adapted to overlie the base forwardly of said opening, a cross brace above said section, said jogged connection forming a cam on the upper side of said section and member adapted to engage said brace and prevent contact of the section with the blade in the insertion and withdrawal of the section to and from its planing position in the base.
